UNITED STATES PATENT OFFICE

WILLIAM LEWELLYN NICOLS, OF TUSCUMBIA, ALABAMA

PREFORMED STEP

Application filed October 5, 1929. Serial No. 397,683.

My invention relates to steps and has for its object the provision of a structure of the character designated which may be easily and inexpensively manufactured and shipped 5 "knockdown" for assembly at the place of use.

An important object of my invention is to provide a novel and effective means to interlock the threads and risers to each other and to the stringers so that, while they are read- 10 ily demountable the treads and risers are nevertheless firmly and positively held in place while mounted on the stringers. My means for locking the three step pieces together is suitable for use with precast con- 15 crete step members and will permit concrete steps to be provided by assembling and interlocking such precast members, or treads or risers may be of wood and the stringers of concrete, or the stringers of wood and the 20 treads or risers of concrete or any other desirable material. My invention is also applicable to the "open" style of steps in which the risers are omitted.

A further object of my invention is to pro- 25 vide a structure which will overcome any possibility of the stringers, when formed of concrete, breaking due to a settling movement of their lower ends which usually rest on the ground without a suitable foundation to sup- 30 port them.

Briefly, my invention comprises a pair of stringers formed of any suitable material, preferably precast reinforced concrete, each of which is provided with a vertical block 35 attached inside at its upper end for engagement with a spacer bar which connects the spaced stringers and is adapted to be secured to a house sill. The desired number of notches are formed along the upper edge of the 40 stringers and suitable demountable locking means are provided for engaging and mounting the treads and risers on the stringers.

A construction embodying features of my invention is illustrated in the accompanying drawing, forming a part of this specification, wherein:—

Fig. 1 is a plan view of the stringers showing the manner of spacing and securing same to the sill of a house, the treads and risers being removed therefrom.

Fig. 2 is an enlarged sectional view taken along the line II—II of Fig. 1.

Fig. 3 is a front elevational view of one of the stringers.

Fig. 4 is an enlarged sectional view taken along the line IV—IV of Fig. 2.

Fig. 5 is a perspective view of a tread.

Fig. 6 is a front elevational view of a riser, and

Fig. 7 is a fragmentary view in side eleva- 60 tion of a modified form of my invention, parts being broken away to show the manner of securing the inner side of a tread when risers are not used.

Referring now to the drawing for a better 65 understanding of my invention, I show a pair of stringers 5 and 6 which are preferably formed of precast concrete and having notches formed along their upper edges adapted to receive treads 7 and 8 and, where 70 such are desired, the risers 9 and 11. An anchor block 12 is secured to the upper end of each stringer by means of bolts 13 which have their heads embedded in their respective stringers and their other ends threaded to 75 receive nuts 14. The stringers are held in a spaced relation to each other by a spacer bar 16 which is secured at each end to an anchor block by nails 17. The spacer bar forms that part of the steps which is secured to a house 80 sill 18, as by nails 19.

The upper tread 7 is secured to the stringers by staples 21, bolts 22 and nuts 23. Each staple has its one leg embedded in a stringer and its other leg engaging the inner 85 edge of the tread, and its intermediate portion stands flush with the rear edge of the stringer and tread 7. T-slots 24 are found in the outer corners of each tread support along the stringers and are adapted to receive the 90 bolts 22 for engagement with the nuts 23 which are embedded in the treads. The tread 8 is secured to the stringers at its outer edge by bolts 26 and nuts 27 in slots 24 which are similar to the bolts 22, nuts 23 and slot 24 95 above described. The tread 8 is also secured at its inner edge by the riser 9 and by plates 28 which are mounted in slots formed at the inside corner of each notch along the stringer and are adapted to engage slots 29 formed 100

in the tread. The riser 9 is secured in position on the stringers by the treads 7 and 8 and the plates 28 which engage the slots 31 formed in the riser.

5 Treads 7 and 8 are formed having shoulders 32 which engage over and clamp the risers 9 and 11 along their upper edges. The tread 8 is formed with a recess 33 into which the lower edge of the riser 9 is seated. The 10 lower edge of the riser 11 is secured to the stringers by means of nuts 34 which are embedded in the stringers and are adapted to engage bolts 35 which extend through holes formed in the riser.

15 Fig. 7 illustrates a modified form of my invention in which, the means for securing the inner end of the tread 36 consists of a plate 37 having its one end mounted in a slot formed in the stringer 38 and its other mounted in a slot formed in the inner edge of the tread. This means for securing the tread at its inner end is employed when risers are 20 not used.

25 In assembling this structure, the anchor blocks 12, which have been secured to the stringers 5 and 6 during the forming operation, have the spacer bar 16 nailed thereto. This part of the structure comprises the frame of the steps which is then secured to 30 the house sill 18 by nails 19 driven through the spacer bar. The upper tread 7 is then mounted across the stringers and is secured in position by staples 21 and bolts 22 which can be tightened by inserting a tool in the 35 slot 24 and turning the bolt to screw it into its respective nut 23 in the tread. The riser 9 is then positioned having its upper edge secured against the vertical face of the stringer 7 by the shoulder 32 formed on the tread 7 40 and the slots 31 formed in its lower edge are engaged by the plates 28. The lower edge of the riser 9 is secured against outward movement by the tread 8 which, in turn, is secured in position by the plates 28 and the bolts 26 and nuts 27. The riser 11 is then 45 interlocked with the stringers by the engagement therewith of the shoulder 32 formed on the tread 8 and by the nuts 34 and bolts 35.

50 Where risers are not used, see Fig. 7, plates are mounted horizontally in slots formed in each stringer 37 and are adapted to engage with suitable slots formed in the rear edge of the tread 36 which has no notch 33 but abuts against the vertical edge of the stringer.

55 Though I have described with great particularity the details of the embodiment of the invention herein shown, it is not to be construed that I am limited thereto, as changes in arrangement and substitution of equivalents may be made by those skilled in the art without departing from the invention as defined in the appended claims.

What I claim is:—

55 1. Steps comprising stringers molded of fire and weather resistant material and pro-

vided with undercut sockets opening through both horizontal and vertical faces of tread supports, and a tread having depending complementary attachment elements adapted to slidably interfit and interlock in said sockets, 70 said attachment elements being bolts and the undercut portion of the socket opening through the front edge of the stringer and enlarged to receive a tool by which the bolts can be engaged and tightened to assemble the 75 treads on the stringers.

2. Steps comprising concrete stringers, concrete treads, means to interlock the treads on the stringers by an inward movement into operating position thereon, risers adapted to 80 interlock top and bottom with the treads, and exposed means to demountably connect the bottom riser to the stringers thereby to interlock all parts in place.

3. Steps comprising stringers, treads, 85 means adapted to interlock the treads on the stringers, said stringers being formed with integral thickened top tread supports having anchor bolts projecting inwardly therefrom and embedded therein, wooden cleats connected to the stringers by said bolts and offset from the rear edge of the stringers, and a tie board spiked to the cleats and adapted to be nailed to the house sill.

4. Steps comprising stringers formed of 90 concrete having suitable tread supports, concrete treads mounted on said supports, a hold-down bolt anchored in and depending from the treads near each end thereof, and means to demountably interlock each bolt to the adjacent tread support, said means permitting the removal and replacement of the tread without disengagement of the hold-down bolts therewith.

100 In testimony whereof I affix my signature. 105
WILLIAM LEWELLYN NICOLS.
